RECEPTACLE COVER SECURING DEVICE

Adrian L. Cooper, Dayton, Ohio

Application June 18, 1951, Serial No. 232,113

1 Claim. (Cl. 292—114)

1

This invention relates to a receptacle cover securing device, and more particularly to such a device adapted for use with trash or garbage cans.

A primary object of the invention is to provide a receptacle cover securing means whereby the cover may be held in operative or inoperative position, so that the cover may not be lost, and further, so that the cover may not be displaced when in operative position.

A further object of the invention is the provision of a receptacle cover securing means which may be readily applied to the receptacle and cover without the use of tools.

Still another object of the invention is the provision of such a device provided with means for connecting the cover handle and the receptacle handles which provides a substitute handle for the receptacle, so that the latter may be carried with the cover securing means in operative position.

Still other objects will in part be obvious and will in part be pointed out as the description of the invention proceeds and shown in the accompanying drawing, wherein there is disclosed a preferred embodiment of this inventive concept.

In the drawing:

Fig. 1 is a fragmentary side elevational view of a receptacle and cover showing the receptacle cover securing means of the instant invention in applied position;

Fig. 2 is a top plan view of one of the receptacle cover securing means shown in Fig. 1;

Fig. 3 is an end elevational view of a portion of the device disclosed in Fig. 2; and

Fig. 4 is a plan view of the blank from which a portion of the device disclosed in Figs. 1 to 3 is formed.

Similar reference characters refer to similar parts throughout the several views of the drawing.

Referring now to the drawing in detail, there is generally indicated at 10 a receptacle such as a garbage or trash can, provided with a conventional cover or lid 11 having a centrally positioned handle 12. The receptacle 10 is provided on its opposite sides with a pair of handles 13, hingedly secured as by hinges 14 to an intermediate point on the side of the receptacle.

The device of the instant invention is adapted to provide a means for securing the cover or lid 11 on the receptacle 10 and includes a means generally indicated at 15 for engaging the handle

2

12, this means including a wire coil comprised of a double loop 16 and 17 connected by a link 18, the loop 16 being adapted to engage about one of the side members of the handle 12. The other loop 17 has secured thereto one end 19 of a coil spring 20, the opposite end of which is engaged in an aperture 21 in a plate generally indicated at 22 formed from the blank of Fig. 4.

The plate 22 has the central portion, as indicated at 23, cut out, and the cutout tongue 23 is looped inwardly, as best shown in Fig. 1, to engage in the bight of handles 13. The outer portion of the plate 22, indicated at 24, is curled outwardly and reverted to form a finger gripping portion to serve as an auxiliary handle in lieu of the handles 13.

From the foregoing, the operation of the device should now be readily understandable. Loops 16 are first secured about the handle 12 and the springs 20 stretched or extended until the reverted portions 23 of plates 22 may be secured in the bights of handles 13. The springs 20 are thus placed under tension, and serve securely to hold the cover 11 in position upon the receptacle 10. If it is desired to move the receptacle 10, the hook-shaped or reverted portions 24 may be utilized as auxiliary handles in lieu of the handles 13, and the device may be readily lifted thereby.

As various embodiments may be made of this inventive concept, and as various modifications may be made in the embodiment hereinbefore shown and described, it is to be understood that all matter herein is to be interpreted merely as illustrative and not in a limiting sense.

I claim:

A cover holding means for a receptacle having a pair of handles and a cover provided with a handle in the center of the top thereof, said cover holding means comprising a pair of springs, securing means for each spring, each securing means comprising an elongated wire formed with a single loop at each end, said loops being on opposite sides thereof, each wire having one loop secured to one end of each spring and the other end secured to the cover handle, means at the other end of each spring comprising a plate having a central cutout reverted portion for securing the other end of each spring to a receptacle handle, and means comprising the portion of said plate from which the cutout is stamped reverted oppositely to said cutout portion to form an auxiliary handle for said receptacle in offset rela-

3

tion relative to said receptacle, said auxiliary handle comprising the exterior rim of said cut-out portion and including a transverse end portion and side portions to afford a handle grip.
